UNITED STATES PATENT OFFICE

ROBERT E. WILSON, OF CHICAGO, ILLINOIS, ASSIGNOR TO STANDARD OIL COMPANY (INDIANA), OF CHICAGO, ILLINOIS, A CORPORATION OF INDIANA

FURNACE STRUCTURE

Application filed March 28, 1930. Serial No. 439,631.

This invention relates to furnace structure and it pertains more particularly to "up-shot" radiant furnaces wherein tubes are spaced around the inner periphery of a furnace and are heated by a central flame from a burner mounted in the furnace base. The products of combustion travel upward through the radiant chamber and are then passed through an economizer section and/or 10 an air preheater. The heat transfer to the tubes is effected by radiation which insures a uniform high rate of heat transfer to each tube under all firing conditions and avoids all tendency to overheat any one tube since 15 all tubes are equally spaced at a safe distance from the flame and perform substantially the same duty. However, in the ordinary design the lower portion of each tube picks up substantially more heat than the upper portion 20 thereof.

The object of this invention is to provide a furnace of this type which will increase the heat input to the upper portion of the tubes so that it substantially equals that to the 25 lower portion, thus increasing the capacity and efficiency of the furnace. A further object is to protect economizers and/or air preheaters which are mounted directly above the furnace from the intense heat radiated from 30 the furnace and from insufficiently cooled gases of combustion.

A further object is to provide a furnace of this type wherein the maximum amount of available heat is utilized by the tubes in the 35 furnace, leaving a minimum amount to be absorbed by economizers and preheaters. Other objects will be apparent as the detailed description of my invention proceeds.

The invention relates to the provision of a 40 baffle to reflect and/or radiate heat toward the upper part of the tubes in the radiant chamber of the furnace, to direct hot gases against the upper portion of said tubes, and to protect the economizer and/or air preheater against direct exposure to radiated 45 furnace heat or direct contact with non-cooled combustion gases.

My invention will be more clearly understood from the description of a preferred 50 embodiment which is illustrated in the ac-

companying drawing wherein similar parts are designated by like reference characters throughout the several views and wherein:

Figure 1 is a vertical section through my improved furnace;

Figure 2 is a partial section through another modification thereof;

Figure 3 is a view of the modified baffle as seen from line 3-3 of Figure 2; and

Figure 4 is a horizontal section taken along 60 the lines 4-4 of Figure 1.

My improved furnace consists of a radiant chamber which may be an upright cylindrical still 10 having a flat top 11. The top is provided with a central aperture over which is mounted the economizer and preheater section 12. This section in turn supports the stack 13. Both the radiant chamber and the economizer and preheater chamber are lined with fire brick or other suitable refractory material 14. The bottom 15 of the furnace has a substantially flat periphery and a depressed central portion through which extends the burner as will be hereinafter described.

All around the periphery of the radiant chamber of my furnace I provide vertical pipes 16 extending through the top and bottom walls of the furnace, and immediately inside these pipes I provide an inner circle 80 of pipes 17, the ends of which also extend through the top and bottom walls. The ends of these pipes are connected by suitable return joints 16a and 17a so that liquid enters an outer pipe, flows through all of the other pipes in series, then flows through all of the inner pipes in series, and is finally discharged therefrom. In the drawing I have only

shown four pipes, two on each side, in order to avoid a confusion of lines. It is to be understood, however, that these pipes are arranged at short intervals all around the circumference of the radiant chamber. Arrangement and flow may be varied without affecting the spirit of my invention.

Air to support combustion enters inlet 18, is heated in preheater 19 and passed around baffles 20 therein, and is then conducted by pipe 21 to the burner 22 in the bottom of the radiant chamber. Fuel is introduced into

this nozzle through pipe 23, and the fuel and air supply are regulated to give a large flame 24 in said chamber.

The oil or other liquid which is to be heated 5 in the furnace is introduced by pipe 25 through preheater or economizer 26 which is usually a plurality of pipes adapted to be connected in series or in parallel. The oil leaves the preheater by pipe 27 which introduces it into the series of outer pipes 16 10 in the radiant chamber. It passes through each of these pipes in series, and then through each of the inner pipes and finally leaves the furnace through pipe 28.

15 It will be observed that the radiant heat from flame 24 will be greater in the lower portion of the radiant chamber than in the upper portion thereof, that there will be a tendency for the hottest gases to travel 20 through the center of the chamber and impinge upon the preheaters without delivering up a sufficient amount of their heat in the radiant chamber. This causes the upper parts of tubes 16 and 17 to be relatively 25 ineffective and it may cause overheating or burning of preheater tubes.

To avoid these difficulties I provide a baffle 29 which may consist of a polished metal facing 30 backed by refractory material 31 30 and supported by chains, links or rods 32. The polished metal and supports must necessarily be of highly refractory metal such as chromium nickel alloys. The baffle may be of various shapes, but I prefer to use a surface 35 of revolution which will not seriously impede the upward flow of gases, which will reflect and radiate heat toward the upper part of tubes 16 and 17, and which will direct the hot combustion gases against said tubes 40 before said gases are discharged into the preheater zone.

In the modification shown in Figure 2 I have employed a plurality of horizontal plates of diminishing diameter. I provide a central support 33 on which are mounted a plurality of plates 34, 35, 36 and 37 of diminishing diameter. This type of baffle is more effective in preventing the radiation of heat from the radiant chamber to the preheater 45 section, and it is also effective in directing gases toward the upper portion of tubes 16 and 17.

I contemplate the use of various other types and arrangements of baffles. The size 50 and shape of the baffle should be designed to promote equality of heat transfer through each square foot of tube surface. With the types of baffles above described, the upper portions of the tubes will be at about the 55 same temperatures as the lower portions and the heat supplied to the tubes will be substantially uniform throughout their entire length. Many modifications, substitutions and equivalents will be apparent to those skilled in 60 the art, and I do not limit myself to the de-

tails hereinabove set forth except as defined by the following claims.

I claim:

1. In furnace structure, a radiant chamber, a plurality of vertical tubes mounted around 70 the periphery of said chamber, a preheater section above said chamber, a burner mounted in the base of said radiant chamber and below said preheater section, and a baffle interposed between said burner and said preheater 75 section to protect the preheater section from radiated hot gases and to direct heat toward the upper ends of said tubes.

2. In a furnace structure, a vertical combustion chamber having a side wall and top 80 and bottom walls, an economizer section above said chamber, means for passing gaseous products of combustion from said chamber through said economizer, means for passing a fluid through said economizer in indirect 85 heat exchange relation to said gaseous combustion products, means for introducing a combustible fuel and air into said chamber whereby said fuel burns therein and liberates heat to the side wall thereof, vertical tubes in said chamber spaced at intervals around said side walls and extending through said top and bottom walls, a baffle in said chamber under said economizer, said baffle having exposed surfaces for reflecting heat and deflecting hot gases against the upper parts of said tube whereby said tubes absorb heat from gaseous combustion products leaving the furnace so that said products will not burn said 90 means for passing said fluid through said economizer section.

3. In a furnace structure, a vertical combustion chamber having a side wall and top 95 and bottom walls, said top wall having a central aperture therein, a preheater section above said aperture whereby hot combustion gases from said chamber pass through said preheater section, a heat exchange conduit in said preheater section, means for conveying a combustible fuel and air into said chamber whereby said fuel burns therein and radiates heat to said side wall thereof, vertical tubes in said chamber spaced at intervals around the side wall and extending 100 through said top and bottom walls, means for connecting said heat exchange conduit with one of said tubes, means for connecting each of said tubes with an adjacent tube whereby 105 fluid may be passed through said tubes in series, and a baffle in said chamber underneath said preheater for reflecting heat and deflecting hot gaseous combustion products against the upper part of the tubes in said chamber whereby heat is absorbed by said tubes from said combustion products so that the hot combustion products will not burn the heat exchange conduit in said preheater.

Signed this 24th day of March, 1930, at Chicago, county of Cook, State of Illinois.

ROBERT E. WILSON.

CERTIFICATE OF CORRECTION.

Patent No. 1,871,937.

August 16, 1932.

ROBERT E. WILSON.

It is hereby certified that error appears in the printed specification of the above numbered patent requiring correction as follows: Page 2, line 77, claim 1, for the words "hot gases" read heat, and for "heat" read hot gases; and that the said Letters Patent should be read with this correction therein that the same may conform to the record of the case in the Patent Office.

Signed and sealed this 22nd day of November, A. D. 1932.
